Specification for Design.

Patented Aug. 26, 1919.

Application filed February 26, 1919. Serial No. 279,450. Term of patent 3½ years.

To all whom it may concern:

Be it known that I, FRED B. HOLLENBECK, a citizen of the United States, residing at Tacoma, in the county of Pierce and State of Washington, have invented a new, original, and ornamental Design for a Badge, Emblem, Button, Pin, Ring-Top, Watch-Charm, or Similar Article, of which the following is a specification, reference being had to the accompanying drawing, forming part thereof.

The figure is a plan view of a badge, emblem, button, pin, ring top, watch charm or similar article, showing my new design.

I claim:

The ornamental design for a badge, emblem, button, pin, ring top, watch charm, or similar article, as shown.

FRED B. HOLLENBECK.
